UNITED STATES PATENT OFFICE

152,048

DESIGN FOR A SCOURING PAD HOLDER

Alexander C. Weiss, Chicago, Ill.

Application November 27, 1946, Serial No. 135,135

Term of patent 7 years

(Cl. D9—2)

To all whom it may concern:

Be it known that I, Alexander C. Weiss, a citizen of the United States, residing at Chicago, in the county of Cook and State of Illinois, have invented a new, original, and ornamental Design for a Scouring Pad Holder, of which the following is a specification, reference being had to the accompanying drawing, forming part thereof.

Fig. 1 is a perspective view of the Scouring Pad Holder, showing my new design.

Fig. 2 is a side view thereof.

Fig. 3 is a top view thereof.

I claim:

The ornamental design for a scouring pad holder, as shown.

ALEXANDER C. WEISS.
